ROAD TAMPING AND MAINTENANCE MACHINE

Application filed May 11, 1928. Serial No. 276,825.

This invention relates to certain new and useful improvements in road and highway maintenance apparatus and it refers more particularly to a machine as specified, having for its principal object the provision of a machine for preparing a permanent road bed either for surfacing with some form of road construction material, or may itself be used as a finished highway due to the manner in which the soil is tamped and packed by the machine.

Another object of the invention resides in the provision of a machine as set forth in the foregoing, provided with a tamping bar of such weight as to strike the earth with terrific force, and its weight, combined with the added impetus given the bar by suitable machinery for so bringing the bar against the earth, is such as to thoroughly and firmly pack the earth and thus create a foundation of permanence for a road or highway.

Still another object of the invention resides in the provision of a tamping bar capable of operatively spanning half the width of the average road or highway, and so arranged, as is the means of operating the bar, to be moved progressively along such road or highway, the bar striking the earth successive blows as the machine is moving, thus enabling the apparatus to cover a considerable area of road with effectiveness.

The invention further aims among its objects to provide an engine, and a means of distributing the power thereof to operate the said tamping bar and to move said apparatus from place to place.

A particularly important object of the invention resides in the provision of an auxiliary tamping member with which said tamping bar co-operates, the function of which is to insure uniformity in the surface prepared by said tamping bar, by becoming operative only when said bar impinges a comparatively soft portion of soil or enters a depression in the earth and sinks below the normal plane, whereupon said auxiliary tamping member is engaged by a portion of said bar and is brought against the earth with equal force equal to that of said bar.

With the foregoing objects as paramount,

the invention has particular reference to its salient features of construction and operation of parts to become manifest as the description proceeds, taken in connection with the accompanying drawings, wherein:

Figure 1 represents a side elevational view of a road tamping machine constructed according to the invention.

Figure 2 is a side elevational view in vertical section.

Figure 3 is an end elevation thereof.

Figure 4 is a detail view of the co-operating relationship between the tamping bar and the auxiliary tamping member, on lines 4-4 of Figure 3, and

Figure 5 is a plan view of the apparatus.

In continuing further in more detail, it may be here stated that in the present day construction of roads, and highways as well as rail roads, the foundation must of necessity be built with a view of permanence, due especially to the heavy traffic to which the roads are subjected, and unless an extremely hard and durable bed or foundation is prepared, the surface is likely to crack and deteriorate under the severe treatment subjected thereto by heavy loads drawn thereover. Even in the laying of concrete foundations for roads and highways, it is essential that a reasonably firm surface be first prepared to insure uniformity before pouring the concrete, to prevent cracking thereof after setting.

Accordingly, the present invention comprehends the provision of a machine having facilities by which it is possible to thoroughly pack and tamp the earth preparatory to constructing a road or highway, or in leveling high points in much used gravel and other roads, and even in preparing road beds in the construction of rail roads.

In the drawings, 1 designates preferably a channel iron chassis, the forward portion of which is mounted upon the usual truck wheels 2 having a truck differential 3 of preferably worm drives. Arranged near the rear of the chassis 1 is a single wheel 4, which, as shown in Figure 2, is adapted to swivel to provide means by which the machine may be guided. This wheel is mount-

ed in a fork 5 supported by a channel iron arch 6 by means of a bearing 7 affixed to said arch and embracing the spindle 8 extending upwardly from the fork 5 and through the top of the arch and upon which is mounted a collar 9.

The steering mechanism consists of a worm gear 10, rigidly mounted on the spindle 8, cooperating with which is a worm 11 mounted upon the end of the steering rod 12, which carries upon its opposite end the steering wheel 13. It will be observed that the steering rod 12 is braced by suitable bearings 14 affixed to the arch 6 and uprights 15 forming part of the upper frame and of which the overhead beams 16 form a continuation. The said beams 16, as apparent in the figures extend at an angle to the forward end of the machine at which point they are affixed to uprights 17 mounted upon the chassis 1.

Due to the great strain and vibration to which the machine is subjected in operation, the frame must of necessity be constructed with a view of great strength and endurance.

Forwardly of the foremost uprights 17 is mounted the guide frame of the tamping bar 18 shown in detail section in Figure 4 and illustrated in its position relative to other elements of the assembly in Figures 1 and 2. This guide frame, it is important to note is so arranged relative to and connected with the chassis 1 of the machine so as to be capable of adjusting itself to the ground surface irrespective of the position of the chassis, that is to say, the frame is arranged to, at all times, when the machine is in operation, be at right angles to the ground surface to enable the tamping bar 18 to engage the ground uniformly.

This guide frame is composed primarily of two frames 19 and 20 joined together at their tops by strips 21 and at their bottoms by side strips 22. The inner frame 19 is supported by rollers 23, pivoted in bearings 24 beneath the base bar 25 of the frame 19, which latter overreaches the sides of the machine chassis by considerable margin. A similar bar 26 is provided at the front of the guide frame and it is to this latter bar that the frame 20 is connected. In further support of the guide frame assembly, in event a depression in the earth is encountered, a structure 27 protrudes from the machine frame 16 at the top, the lateral portion thereof embracing the front of the outer frame 20, to hold the guide frame assembly against an inclination to lean away from the machine frame. As shown particularly in Figures 1 and 5, a cleat 28 is affixed to either side of the frame 19 of the tamping bar guide frame assembly, and which embraces, in the manner shown in Figure 5, the uprights 17 of the machine frame. These cleats are so arranged as to allow for a considerable amount of universal play between the guide frame and

the machine frame proper during operation of the machine. Intermediate the inner and outer frames 19 and 20 respectively is situated a vertical member 29 supporting bearings 30 in which the ends of shafts 31 are disposed, the other ends of these shafts are supported by bearings 30 mounted oppositely in outer frame 20. These rollers have preferably a surface covered by some form of elastic or yieldable material such as rubber or fiber, the purpose of which will be later made clear.

Intermediate the said member 29 and outer guide frame 20 is situated for independent vertical movement the tamping bar frame composed of vertical members 33, joined together at their tops by head piece 34, and rigidly connected to the tamping bar.

As mentioned previously, the lateral bar 25 overreaches the side of the machine chassis 1, as does the forward bar 26, to which the outer guide frame 20 is secured, and intermediate these frames 19 and 20, the tamping bar 18 is operative and is also of such length as to extend well beyond the sides of the machine chassis, as may be seen in both Figures 3 and 5. In so extending the elements constituting the tamping assembly, a greater operative area is had, and it is the purpose to afford an area of sufficient width as to cover half of the average road bed. However, in so extending the operative area, suitable supports must be provided to stabilize the outer ends of the elements composing the tamping bar guide frame as well as the tamping bar itself. Such supporting means is preferably in the form of angular braces 35 extending from the outer ends of bar 25 upward to the top of the inner guide frame 19; similar braces 36, extending from the outer ends of the tamping bar 18 to the top of the tamping bar frame 33, and braces 37 arranged in a similar manner for supporting the outer ends of the outer bar 26 relative to the outer guide frame 20. Due to the enormous weight and the obvious strain upon the tamping bar frame 33, a greater number of such braces are provided to support the bar 18 relative to said frame, and as shown in Figure 3, bear the same character of reference, 36.

It is now obvious from the foregoing, that the tamping bar guide frame assembly, composed of inner and outer frames 19 and 20, respectively and their associated elements, is capable of comparatively free movement relative to the machine chassis as hereinbefore mentioned, to adjust itself to the function and varied positions of the tamping bar proper during operation thereof. The assembly, during such operation of the tamping bar however, normally rests upon the rollers 23 affixed to the bar 25. Consequently, in event of lateral side swing of the bar the greater pressure will be imposed upon one or the other of these rollers.

In Figure 3 especially, it will be noted that the inner surfaces of the vertical members 33 constituting the tamping bar frame are engaged by the rollers 32 arranged in spaced relationship intermediate the inner and outer guide frames 19 and 20. Thus, frictional wear upon the tamping bar frame is minimized, and further, such an arrangement affords greater freedom of movement of the frame in its vertical travel.

Referring again to Figures 1 and 2 especially, a working beam 38 is mounted at one end upon a lateral shaft 39, in turn mounted in bearings 40 affixed to uprights 15 supporting the upper machine frame 16. This beam extends forwardly of the machine and between the uprights of the guide frame assembly, as particularly shown in the front elevational view in Figure 3. The forward or operative end of the beam 38 is slotted as shown and has bearings 41 mounted to oppose said slot, and which bearings receive the lateral pins 42 of a collar 43. This collar is freely slidable on a lift rod 44, vertically arranged relative to the tamping bar 18 and affixed thereto in the manner shown in Figures 2 and 3, in providing a ball housing or socket 45 encasing a ball fixed to the end of the rod 44, thus providing a universal joint between the lift rod and tamping bar.

The collar 43 is opposed on the lift rod 44 by compression springs 46 as shown, which latter are constrained against movement or displacement by stop collars 47. This arrangement affords a means for absorbing the shock created by the obvious force in which the tamping bar 18 is brought into contact with the earth, and to prevent jarring other than the bar 18 and its frame.

The machinery for actuating the beam 38 and consequently the tamping bar is better illustrated in Figures 2 and 5. A motor 48 is provided, of suitable horsepower, and is of the type having an auxiliary power take-off unit, which, in the drawing, Figure 5, is designated at 49. It is obvious that greater power is required to operate the tamping bar than is required to propel the machine, hence, the engine 48 is offset in the manner shown in order to bring the power take-off shaft into alignment with the propeller shaft 50 of the machine, thereby to drive the differential 3 from the power take-off unit to propel the wheels 2, while the transmission of the engine 48 is brought to one side from which the shaft 51 is driven which shaft operates the working beam 38 in the manner to be presently described.

Arranged oppositely upon the chassis 1 of the machine is a pair of standards 52, supporting a lateral crank shaft 53, and to the crank 54 thereon is mounted the end of a connecting rod 55, the other end of which is connected, as shown in Figures 1 and 2 to the working beam 38.

In driving the crank shaft 53, a large worm gear 56 is mounted thereon as shown in Figures 2 and 5, co-operating with which is a worm 57 mounted on shaft 51 from the engine 48. Hence, all of the speeds of the engine may be transmitted to either the working beam 38 or to the wheels 2 to operate the said tamping bar during movement of the machine along the road.

Reference now is made to Figure 4 wherein is shown a sectional detail view of the tamping bar 18 and associated elements on line 4-4 of Figure 3. An auxiliary tamping member 58 is provided, and is adapted to co-operate, or be operated by the tamping bar 18, in event the latter, when operating in relatively soft ground, sinks below its normal limit of travel, determined by the compactness of the earth.

This member 58 is suspended by bolt 59, yieldingly held relative to a projection integral with the inner bar 25 of the guide frame, by a compression spring 61. A shoulder 62, longitudinally arranged on the tamping bar, is adapted to contact with the auxiliary tamping member 58 and carry the same downward against the earth against the tension of spring 61. A layer of compressible material 63 is applied to the striking face of the auxiliary tamping member 58 as shown in Figures 2 and 4 to prevent undue wear and possible injury to either of the tamping members 18 and 58 by the forceful contact of the shoulder 65 against said member 58.

The member 58, after having been driven down by the bar 18, recedes to normal inoperative position as shown in Figure 4, by the action of spring 61, until such time as the bar 18 again strikes soft soil, whereupon the shoulder is brought into contact with the member 58 and it is again brought forcefully down against the earth.

In normal operation of the machine, the rollers 23 supporting the guide frame roll upon the ground, but in event it is desired to transport the machine from place to place with relatively increased speed, it is desirable that the entire guide frame be elevated to a higher position to lift the rollers 23 off the ground. This is accomplished by providing a shaft 64 arranged laterally across the uprights 17 at the forward end of the machine and mounting on said shaft a winch 65, a cable 66 is arranged on this winch and is connected, as shown in Figure 2 exclusively, at a to the lower part of the inner frame 19 of the guide frame assembly. A ratchet lever 68, shown in Figure 1 is arranged to rotate the winch 65 to wind the cable 66 there-around and thus elevate the guide frame assembly. It has not been considered necessary to go into great detail regarding the elevating means, since such means is old in the art, and in the present case consists simply of 130

a conventional type of winch and ratchet and pawl mechanism.

It will be observed in Figure 5, a plan view, that extensions 69 are applied to the brake and clutch pedals of the engine 48 in order that the operator may conveniently operate the engine and at the same time observe the work of the machine. It is of course understood that this feature as well as other features of the invention may be changed from time to time as is considered practicable for the further development of the machine.

In operation, the machine is driven down a road slowly and the tamping bar 18 put into operation to reciprocate against the earth, its speed being governed according to the speed at which the machine is moving. It is possible to reciprocate the bar at a speed of approximately 60 revolutions per minute without any loss in its effectiveness at less speed, consequently it is obviously possible to cover a considerable area in a very short period of time as compared with other maintenance machines.

In road maintenance work, that is, roads over which the passage of vehicles have made the surface irregular and difficult to traverse in comfort, the present invention is valuable in reducing the high points to a uniform level surface of comparative permanence, due to the compressed condition of the soil or material after having passed the machine thereover.

I claim:

1. A machine and apparatus of the character described including a wheeled frame and a tamping bar arranged at the end of said frame for vertical reciprocation; means for operating said bar, and an auxiliary tamping member co-operating with said bar, and adapted to be operated thereby when the latter moves beyond its normal limit of travel.

2. A machine of the character described including a wheeled frame and a means for propelling the same; a tamping bar arranged in said frame and adapted to be forcibly brought against the earth successively; means for transmitting operating power to said tamping bar from said propelling means, and means adjacent said tamping bar and adapted to be operated thereby to maintain uniformity of surface tamped by said bar when the consistency of said surface permits the latter to move beyond its normal limit of travel.

3. A machine of the character described including a wheeled frame and a propelling means therefor; a tamping bar having an elongated operative surface so arranged in said frame as to be capable of vertical reciprocative movement relative to the earth over which said machine travels; means for transmitting operating power to said bar from said machine propelling means, and means co-

operating with said bar to maintain uniformity of the surface tamped by said bar.

4. A machine for leveling and tamping roads having a weighted tamping element mounted in a frame and operating perpendicularly with respect to said road, means to actuate said tamping element to bring the same successively into forcible contact with the earth when said machine progresses thereover, and means cooperating with said bar to maintain uniformity of the surface tamped by said bar.

5. A road building and maintenance machine having a tamping element operating perpendicularly in a frame with respect to said road and adapted to be brought into forcible contact with the earth as said machine is transported thereover, an auxiliary tamping member arranged to be engaged by said element when this latter has descended a predetermined degree whereby to bring said auxiliary tamping member into contact with the surface tamped by said element when the latter is urged below its normal limit of travel.

6. A road building and maintenance machine having a tamping element operating perpendicularly in a frame and capable of adjusting itself to the surface of said road and an auxiliary tamping member arranged to be engaged by said tamping element and brought thereby into forcible contact with said road surface when said tamping element is urged below its limit of travel.

7. A road building and maintenance machine having a tamping element arranged for reciprocation in a frame vertically with respect to the surface being tamped, an auxiliary tamping element arranged in parallel relationship with said first element and capable of being brought into forcible contact with said road surface when said first element is urged beyond its normal limit of travel, means for operating said elements, means to cushion the shock created by impact of said elements with said surface, with respect to said element operating means.

8. A road building and maintenance machine including a wheeled frame and a tamping element arranged to reciprocate vertically with respect to said road; a guide frame therefor; an auxiliary tamping member relative to said tamping element and adapted to be operated by said tamping element, yieldable means for holding said auxiliary tamping member in inoperative position relative to said guide frame and tamping element, said means also arranged to relieve said guide frame of the shock created by impact of said tamping element with said auxiliary tamping member, and means to elevate said guide frame, tamping element and auxiliary tamping element.

In testimony whereof I affix my signature.
WALTER W. FOSTER.
